WARNING LIGHT

Eugene L. Kilbourn, Marengo Township, Calhoun County, Mich., assignor to S. H. Leggitt Company, Marshall, Mich., a corporation of Michigan

Filed Oct. 7, 1963, Ser. No. 314,392

9 Claims. (Cl. 67—111)

The present invention generally relates to a lighting device and more specifically relates to a flashing, combustible gas, warning light.

Previous warning lights powered by combustible gas and providing a source of flashing light have presented a number of operational and economic problems. For example, such lights have often used fuels including heavy ends which tend to become deposited upon the working parts of valves and similar devices within the structure of the warning light whereby operation thereof is substantially degraded or, in some cases, completely stopped. One occurrence of this problem has been on some warning lights fueled by propane gas derived from pressurized liquid propane.

Some previous warning lights of the type described have included a continuously burning pilot light for igniting spaced pulses of combustible gas, which ignition causes the flashing characteristic of the warning light. In many cases, it has been generally found more economical in such lights, or otherwise preferable, to provide a single burner which produces both the pilot light and the larger flashing light. However, in such cases, water vapor or other impurities in the combustible gas, introduced thereto before the gas reaches the burner, may condense before reaching the burner and may reach same in a liquid condition thereby tending to extinguish the pilot flame.

Another problem has involved the production of an interrupted flow of gas for producing the desired flashing action. It is usually desired that the main gas supply be turned on and off in an abrupt manner whereby the light produced appears to move between its on and off states virtually instantaneously for maximum attention-getting effectiveness. It is also desirable from the standpoint of simplicity and economy, as stated above, to utilize the same burner for the pilot and main flames. Hence, the problem often arises of the virtually instantaneously turning on of the main supply of gas causing a surge in the gas-air mixture surrounding the burner which tends to blow out the pilot flame. The problem may be cured to some extent by increasing the size of the pilot flame but this may not be feasible in cases where the warning light must operate unattended for extended periods on a limited amount of fuel. It is further undesirable because such an increase in the size of the pilot flame effectively raises the light level of the warning light during its idle condition whereby to reduce the contrast in light output between the on and off conditions.

The device of the present invention was developed to overcome these and other problems associated with previous warning lights. More specifically, the device of the invention was developed for use with a liquid propane tank fuel supply and for use as a land-based warning light. However, it will be recognized that the device of the invention may be used in other environments and may utilize different forms of fuel. Hence, the embodiment of the invention hereinbelow described will, for purposes of illustration only, be of the land-based type and will utilize tanked liquid propane as a combustible gas source.

Accordingly, the objects of this invention include:

(1) To provide a flashing warning light fueled by a combustible gas.

(2) To provide a device, as aforesaid, particularly adapted for use with propane gas derived from a storage tank of liquid propane.

2

(3) To provide a warning light, as aforesaid, including a continuously burning pilot flame and wherein the pilot and main flames issue from the same burner.

5 (4) To provide a cracking tube to fraction out sludge elements or heavy ends in the fuel supply whereby clogging of the valves in the system is sharply reduced or eliminated.

(5) To provide a device, as aforesaid, including a shock chamber for controlling the character of the pressure change at the burner during the turning on or shutting off of the main gas supply.

(6) To provide a device, as aforesaid, including an evaporation tube to prevent collection of moisture in the burner which could otherwise extinguish the pilot light.

(7) To provide a device, as aforesaid, incorporating a pair of chambers which is mountable on existing propane tanks.

(8) To provide a device, as aforesaid, including a minimum number of parts consisting mainly of either stock or easily fabricated parts which are generally inexpensive and which are capable of quick and easy assembly by relatively inexperienced personnel to produce a unit at relatively low cost.

(9) To provide a device, as aforesaid, which is capable of operation under a wide diversity of weather conditions, is easy to put into operation, needs little or no maintenance over long periods of time, is easily repaired with simple tools and by persons of little experience, is sturdily built, and is economical of fuel.

30 Other objects and purposes of this invention will become apparent to persons acquainted with this type of equipment upon reading the following description and inspecting the accompanying drawings.

In the drawings:

35 FIGURE 1 is an oblique view of the warning light embodying the invention.

FIGURE 2 is a diagrammatic view disclosing the sequence of connections of the gas-carrying parts of the device of FIGURE 1, the tank being shown for convenience at a small scale and the remaining parts at a large scale.

FIGURE 3 is an exploded, oblique view of the gas-carrying parts and lines and the hood structure of the device of FIGURE 1.

FIGURE 4 is a partially broken three-quarter size elevational view of the hood of FIGURE 1.

45 Certain terminology will be used in the following description for purposes of convenience in reference only and is not believed or intended to be limiting. For example, the words "upwardly," "downwardly," "rightwardly," "leftwardly," "frontwardly" and "rearwardly," derivatives thereof and words of similar import will apply to the warning light of FIGURE 1 or to parts thereof being described. The terms "inwardly" and "outwardly" will refer to the geometric center of the warning light or to parts thereof being described.

General description

In general, the objects and purposes of this invention are met in providing a flashing warning light lighted by the intermittent combustion of a combustible gas, such as 60 that derived from liquid propane. Closure means, mounted on and supported by a fuel tank, is divided into a pair of chambers by a baffle plate. The upper of said chambers houses the pilot and main flames, pulse-producing means, cracking and evaporation tubes and means controlling the characteristics of the main and pilot flames. Said upper chamber has at least partially transparent walls 65 allowing said flames to be visible from outside thereof. The lower chamber houses suitable pressure-regulating devices and the burner. The aforementioned gas-handling devices are mounted on the baffle plate.

The cracking tube comprises a piece of gas-conveying

tubing lying within the upper or flame chamber and exposed to the heat of said flame to crack or cause changing of sludge components of the combustible gas into lighter ends subject to combustion and incapable of interfering with the operation of the valves of the system. The evaporation tube comprises a piece of gas-conveying tubing lying within the upper or flame chamber and subject to heating by the flame to vaporize water or other liquids within said tube to prevent extinguishing of the pilot flame thereby. The shock chamber is provided for controlling the time rate of change of pressure of the main gas charge at the burner to prevent blow-out of the pilot flame thereby.

Detailed description

FIGURE 1 discloses a warning light structure 10 including a fuel tank 11 which in this embodiment is a conventional liquid propane tank of a widely available commercial type. The tank 11 has a valve 13 mounted on top thereof and communicating therewith for controlling the flow of propane gas to a check valve 14. The valve 13 allows the tank 11 to be completely manually shut off. The check valve 14, which may be of any convenient type, also functions as a safety valve and shuts off the gas supply when the rate of flow therethrough exceeds a safe maximum.

The tank 11 supports and has affixed thereto by any convenient means, such as welding, a semicylindrical collar 16 which preferably partially surrounds the valve 13. The collar 16 preferably has its open side closable by a suitable door 17 which is hingedly attached thereto and which, when closed, defines with the collar 16 a cylindrical lower chamber 18.

A housing 21 includes an essentially circular base plate 22, to the upper face of which is affixed a generally U-shaped hood 23 which has upstanding end walls, one of which is shown at 26 (FIGURE 3). The housing 21 defines therewithin an upper or flame chamber 27. The housing 21 is supported by the collar 16 and the base plate 22 covers the upper end of the lower chamber 18. The housing 21 is secured to the collar 16, preferably hingedly, by means not shown, whereby the base plate 22 may be moved away from the chamber 18 for inspection or the like. The housing 21 may include a downwardly slidable inspection cover 28 for allowing examination of the flame chamber 27. The housing 21 may also include a vent cover 29 to permit the escape of products of combustion from the flame chamber 27. Lenses 31 and 32 are fixed by a convenient means, such as the screws 33 (FIGURE 3), to the end walls, such as the end wall 26, of the housing 21 for visually indicating the presence of a flame within the flame chamber 27.

Referring now to FIGURE 2, the gas-feeding circuit 40 is, generally speaking, comprised as follows: the tank 11 feeds, through the on-off valve 13 and check valve 14, a series pair of pressure regulators 49 and 56 which are of any convenient type capable of delivering gas at a reduced, non-fluctuating pressure level. Said regulators are then connected through a cracking tube 58 to a branch block 62 which allows diverging gas flow into two different paths, hereinafter described, and controls the relative flow thereto by inclusion therein of needle valves 63 and 64. One branch of the branch block 62 feeds a burner 67 a sufficient, and constant, amount of gas to produce a pilot flame. The other branch feeds a pulsating valve 73 which intermittently turns on and shuts off the supply of gas therethrough to produce a pulsating gas flow. The pulsating valve 73 connects through a shock chamber 76, dwell valve 77 and evaporation tube 81 to the other side of the burner 67 whereby to supply a pulsating flow of gas for a pulsating main flame.

FIGURES 3 and 4 are more complete representations of the gas-carrying circuitry of the invention in which

the main components are arranged in the same sequence as in the diagrammatic representation of FIGURE 2. In FIGURES 3 and 4 the check valve 14 connects the valve 13 of the tank 11 through suitable fittings 42 and 43, a high pressure hose 44, and a further fitting 48 to the first gas-pressure regulator 49. Said first regulator 49 drops the pressure of the gas exiting therefrom to a level below the pressure of the gas in the tank 11 and somewhat above the pressure at which said gas is to be utilized, said output pressure being variable over a limited range depending on variations in the tank pressure in accordance with known operation of gas pressure regulators.

The output of the regulator 49 connects through a fitting 51, tube 52 and fitting 53 to the second regulator 56 which drops the pressure of the gas emerging therefrom to the level required by the succeeding parts of the circuit. Such pressure will be variable only over a very narrow range despite wide variations in tank pressure in accordance with standard series gas pressure regulator operation. The output of the secondary regulator 56 connects through a suitable fitting 57 to the input end of the cracking tube 58.

The lines "A," "B," "C" and "D" in FIGURE 3 denote the points at which elements of the gas circuit covered thereby pass through base plate 22. Thus, the placement of the line "D" indicates that the regulators 49 and 56, the means connecting same to the valve 13 on the tank 11, the fitting 57 and the lower end of the cracking tube 58 are located below the base plate 22 and, hence, within the lower chamber 18 (FIGURE 1). The upper part of the cracking tube 58, on the other hand, is above the line "A" and, thus, is located within the flame chamber 27 of the housing 21. The cracking tube 58 preferably enters said flame chamber 27 from the lower chamber 18 through a suitable opening in the base plate 22 (not shown).

The output end of the cracking tube 58 connects through a fitting 61 to the branch block 62 whereby gas is channeled through the valve 64 and a connecting tube 66 to the burner 67. The tube 66 passes from the branch block 62 downwardly through the base plate 22 at a point indicated by the line "B" in FIGURE 3 so that its output end lies below said base plate 22. The input openings of the burner 67 are also located below the base plate 22 and the output nozzle thereof rises at the line "C" upwardly through said base plate 22 into the flame chamber 27 whereby gas escaping from the nozzle 67 and a flame fed thereby appear in the flame chamber 27.

The gas supply from the cracking tube 58 is also conveyed through the valve 63 in the branch block 62 and hence through a suitable tube 71 and fitting 72 to the pulsator valve 73 which periodically interrupts the flow of gas therethrough in a manner to provide a pulsating gas supply at its point of discharge. The pulsating valve 73 may be of any convenient type, such as that described in my copending application Serial No. 290,384.

The shock chamber 76 fed by the pulsating valve 73 constitutes merely a short conduit of enlarged diameter and has an internal volume per unit length greater than that of the line to which it is connected. Thus, a rapid change in pressure presented at the input end of said shock chamber 76 appears at the output end thereof as a relatively slower change in pressure due to the enlarged volume of said shock chamber and the finite time required to change the pressure therewithin. A suitable fitting 78 connects the shock chamber 76 to the evaporation tube 81 which then passes downwardly through the base plate 22 at point "D" and thereafter connects to the main flame inlet of the burner 67. The fitting 78 includes a dwell valve 77 for regulating the flow of gas therethrough.

Operation

The tubes 58 and 81 are preferably sufficiently close to the flame of the burner 67 as to be heated thereby but are preferably located so as not to shield the lenses 31 and 32 from the flame of said burner 67.

A flame-shaping device 87, here shown as being of a type similar to that of my copending application Serial No. 314,393 entitled "Flame Shaper and Luminosity Control" is contained within the flame chamber 27 and is connected to the outlet end of the burner 67 by means such as a nut 88.

Although the operation of the device of the invention has been indicated somewhat hereinabove, it will be further detailed hereinbelow for purposes of clear understanding.

Upon opening of the valve 13, gas under pressure flows from the tank 11 and through the regulators 49 and 56, respectively, which operate in a conventional manner to assure that the pressure of the gas exiting therefrom will remain within relatively narrow margins. Thereafter, the gas flows through the cracking tube 58 which, through the valve 64 of the block 62, supplies the pilot gas flow to the burner 67. The pilot flame may now be ignited by any convenient means such as opening the cover 28 and manually igniting the pilot flame. The cracking tube 58, due to its presence in the flame chamber 27 and, more specifically, due to its proximity to the flame of the burner 67, is heated by the main flame when same is burning so that the gas flowing therethrough is heated. Sludge or heavy fractions present in the gas which might cause the clogging or malfunction of valves in the succeeding lines are cracked by the heat imposed thereupon in a well-known manner to become lighter ends which will not clog succeeding valves. A part of the gas so treated passes through the valve 64 of the block 62 to continue to supply the pilot flame, said valve 64 being adjusted to a pilot flame of the proper height.

Gas also flows through the valve 63 in the other leg of the branch block 62 and enters the pulsator valve 73. The pulsing rate of the pulsator valve 73, if same is of the type disclosed in my copending application Serial No. 290,384, is determined by the rate of pressure build-up of gas admitted thereto and, hence, by the setting of the valves 63. The pulsator valve 73 feeds its gas output pulses, which have relatively fast rise and fall times, to the shock chamber 76 which slows down the rate of pressure rise and fall sufficiently that the pressure wave-fronts emitted therefrom will not tend to blow out the pilot light in the burner 67. The gas then flows through the dwell valve 77, adjustment of which controls the amount of time during which the pulsating valve 73 will remain open to discharge its contents sufficiently that its internal pressure will drop and enable it to close. Hence, the dwell valve 77 controls the period of time during which the main flame of the burner 67 will remain on.

The gas then flows into the evaporation tube 81 which is positioned within the flame chamber 27 and adjacent the flame from the burner 67 whereby the contents thereof are heated sufficiently to vaporize water or other liquid contaminants which might be contained therein and which, if allowed to enter the burner 67, might drown out the pilot flame. The gas then enters the burner 67 to be ignited by the pilot flame whereby a pulsating main flame is produced.

Although a particular embodiment of the invention has been disclosed hereinabove for purposes of illustration, modifications or variations thereof which lie within the scope of the appended claims are fully contemplated.

What is claimed is:

1. In a gas fueled warning light, the combination comprising:

- a source of combustible gas;
- pressure regulating means connected to said source;
- cracking tube means connected to said regulating means;

70

gas flow diverging means connected to said cracking tube means and including valve means for controllably distributing gas from said valve means to two selected points;

burner means connected to one of said points; pulsating valve means connected to the other of said points for alternately allowing and preventing the flow of gas therethrough; shock chamber means fed by said pulsating valve means for altering the rate of change of pressure of gas supplied thereto by said pulsating valve means and dwell valve means connected to said shock chamber means for controlling the rate of gas flow therethrough;

evaporation tube means connecting said dwell valve means to said burner, said cracking tube means and evaporation tube means being located in proximity to said burner;

whereby said burner heats said cracking tube means to render valve fouling components carried by said gas incapable of fouling valves and heats said evaporation tube means for vaporizing liquid therewith.

2. The device defined in claim 1 wherein:

said fuel source comprises a container of liquid propane;

and

including a collar fixed to said tank; and a housing comprising a base plate fixed to a hood member, said housing defining an enclosed flame chamber, said base plate being mounted upon the outward end of said collar for defining therewith a lower chamber;

said regulating means, said cracking tube means, said diverging valve means, said pulsating valve means, said shock chamber means, said dwell valve means, said evaporating tube means and said burner means being fixed to said base plate whereby said fuel tank may be detached from the rest of the warning light by disconnection of said regulating means therefrom and by disconnection of said base plate from said collar.

3. The device defined in claim 2 wherein said regulator means mounts upon the lower chamber face of said base plate;

said burner mounts on the lower chamber face of said base plate and projects therethrough for emitting gas into said flame chamber;

wherein said evaporation tube means, said diverging valve means, said shock chamber means, said dwell valve means and said cracking tube means lie in said flame chamber.

4. In a gas fueled warning light, the combination comprising:

a tank for holding a combustible gas under pressure; a housing and a partition in said housing for defining a combustion chamber above said partition, said combustion chamber having at least one light emitting lens;

a burner fixed with respect to said partition and extending upwardly therethrough into said combustion chamber;

a gas-flow divider located in said combustion chamber and valves in said divider adjustable to set gas flow therefrom;

means connecting said tank to said divider; means connecting one branch of said divider to said burner and adapted to produce a pilot flame at said burner;

means including a pulsating valve disposed in said combustion chamber connecting the other branch of said divider to said burner for intermittently supplying combustible gas thereto in quantities adapted to produce a main flame;

whereby a plurality of successively appearing main flames can be ignited from said pilot flame and will

75

transmit intermittent pulses of light through said lens. 5. The device defined in claim 4 including a tube positioned at least partially within said combustion chamber and adjacent said burner and connected in series in the line between said tank and said divider for heating said tube to prevent the contents thereof from fouling said valves.

6. The device defined in claim 4 in which said last named means includes an evaporating tube positioned at least in part within said combustion chamber and adjacent said burner and connected in series with said burner and said pulsating valve.

7. In a gas fueled warning light, the combination comprising:

a source of combustible gas; 15 pressure regulating means connected to said source; gas flow diverging means including valve means for controllably distributing gas from said valve means to two selected points;

burner means connected to one of said points; first tube means located adjacent said burner for heating the contents thereof to prevent fouling of succeeding components, said first tube means connecting said regulating means to said diverging means; pulsating valve means connected to the other of said points for alternately allowing and preventing the flow of gas therethrough;

shock chamber means fed by said pulsating valve means for altering the rate of change of pressure of gas supplied thereto by said pulsating valve means and dwell valve means connected to said shock chamber means for controlling the rate of gas flow therethrough;

second tube means located adjacent said burner for heating the contents thereof to vaporize liquid impurities therewithin, said second tube means connecting said dwell valve means to said burner;

5

10

20

25

30

35

whereby said first tube means tends to maintain said valve means, pulsating valve means and dwell valve in a nonfouled condition and said second tube tends to prevent drowning of said burner.

8. In a warning light, the combination comprising: a source of combustible gas; a burner;

a passageway between said source and said burner for supplying a flow of gas to said burner, two spaced portions of said passageway being disposed for heating by said burner;

a pulsating valve in said passageway between said two portions for rendering said flow of gas intermittent; and

a pilot passageway extending between the first-mentioned passageway and said burner, said pilot passageway being connected with the first passageway at a point between said pulsating valve and the one of said portions nearest said source for maintaining a constant pilot flame at the burner.

9. The device defined in claim 8, including an enlarged shock chamber disposed in said first passageway near said pulsating valve.
